FRIEDRICH W. MEYER, OF PITTSBURGH, PENNSYLVANIA, ASSIGNOR TO WESTINGHOUSE ELECTRIC AND MANUFACTURING COMPANY, A CORPORATION OF PENNSYLVANIA.

RECTIFYING SYSTEM.

1,286,050.

Specification of Letters Patent.

Patented Nov. 26, 1918.

Application filed March 24, 1915. Serial No. 16,676.

To all whom it may concern:

Be it known that I, FRIEDRICH W. MEYER, a subject of the Emperor of Germany, and a resident of Pittsburgh, in the county of Allegheny and State of Pennsylvania, have invented a new and useful Improvement in Rectifying Systems, of which the following is a specification.

My invention relates to the art of current rectification by means of vapor arcs, and it has for its object to provide means whereby, when current from a plurality of independent circuits is rectified in one evacuated space, the rectifying arcs may be maintained entirely separate and distinct from each other.

In the accompanying drawing, Figure 1 is an end view, in section, of a rectifier embodying my invention; Fig. 2 is a side view, 20 in section, of the rectifier shown in Fig. 1; and Fig. 3 is a side view, in elevation, of a compound rectifier embodying a modification of my invention.

In Patent No. 1,253,267, issued to the 25 Westinghouse Electric & Manufacturing Company on Jan. 15, 1918, on an application filed by myself, I have described and claimed a system wherein current from a plurality of distinct circuits is rectified simultaneously within a single rectifier. The 30 system therein disclosed operates satisfactorily in all cases where the only connection between the different circuits is at the common cathode, but, when there is a difference of potential between two or more vapor arcs, as, for example, when two rectifying arcs are operating in series with each other to supply a single load, there is a tendency for coalescence between the two 35 arcs, with consequent elimination of a portion of the circuit. In accordance with my present invention, I effectively prevent this harmful action by restricting communication between the different arc spaces to only 40 such an amount as is required for pressure equalization, and I provide means for producing a magnetic blowout flux in the restricted communicating space, whereby, if either arc tends to trespass upon the space 45 of the other, it is immediately forced back or extinguished by magnetic action.

Referring to the form of my invention shown in Figs. 1 and 2, a closed container 4 is provided with suitable anodes 5—5 and 4—6 and with cathodes 7 and 8 associated

respectively therewith. The container 4 is preferably constructed of a non-magnetic mercury-resisting metal, such, for example, as nickel-iron alloy, for a purpose to be hereinafter pointed out. The cathodes 7 60 and 8 are insulated from the container 4 by suitable insulating cups 9 and 10. Current derived from a supply system 11 is rectified through the joint action of the anodes 5—5 and the cathode 6 and is supplied to any suitable load 14. In like manner, current derived from a system 13 is rectified by the joint action of the anodes 6—6 and the cathode 8 and supplied to a conductor 12 in series with the first named 70 rectifying system. In order to effectively separate these two rectifying arcs, the interior of the container 4 is divided into two chambers 15 and 16 separated by a composite perforated partition comprising 75 refractory members 17 and 18 of non-magnetic material, such, for example, as porcelain, and members 19 and 20 of magnetic material. The various members of the above mentioned partition are fitted together to form a central opening 21 connecting the spaces 15 and 16, allowing pressure equalization therebetween and ready evacuation of the container by a single pump. An electromagnet 22, energized 80 from a suitable source 23, embraces the container 4 and presents its pole faces opposite the outer edges of the magnetic members 19 and 20, thus maintaining a strong magnetic flux across the opening 21. 90

In the operation of my device, rectifying arcs may be started and maintained in both chambers 15 and 16 by any suitable means and will operate to rectify current from the two systems 11 and 13. When either 95 arc attempts to strike over into the chamber occupied by the other arc, because of the difference of potential therebetween, it will be diverted or extinguished by the action of the magnetic flux in the space 21 and coalescence of the arcs, with consequent disturbance and undesired current interchange between the two systems, will be effectively prevented.

In the form of my invention shown in 105 Fig. 3, two vapor rectifiers 24 and 25 of the usual type are connected by a tube 26 so that they will be maintained at like pressures and may be evacuated simultaneously. An electromagnet 27 embraces the 110

2
tube 26 and performs a function exactly similar to that of the magnet 22 in the form of my invention shown in Fig. 1.

While I have shown my invention in two 5 distinct embodiments, it will be apparent to those skilled in the art that it is susceptible of various minor changes and modifications without departing from the spirit thereof and I desire, therefore, that no limitations 10 shall be placed thereupon except such as are imposed by the prior art or are specifically set forth in the appended claims.

I claim as my invention:

1. In a vapor rectifier, the combination 15 with a plurality of rectifying arcs, of dynamic means for preventing said arcs from coalescing, said means permitting the free passage of gases from one arc space to the other.
2. In a vapor rectifier, the combination 20 with a plurality of rectifying arcs, of magnetic means for preventing said arcs from coalescing.
3. In a vapor rectifier, an anode and a 25 cathode associated therewith, another anode and an additional cathode associated therewith, and dynamic means for preventing arcs between each pair of electrodes from coalescing.
4. In a vapor rectifier, an anode and a 30 cathode associated therewith, another anode and an additional cathode associated therewith, and magnetic means for preventing arcs between each pair of electrodes from coalescing.
5. The combination with an evacuated 35 container, of a perforated partition dividing the interior thereof into two chambers, and means for maintaining a distinct rectifying arc in each of said chambers.
6. The combination with an evacuated 40 container, of a perforated partition dividing the interior thereof into two chambers, means for maintaining a distinct rectifying arc in each of said chambers, and means for preventing each of said arcs from striking over into the other chamber.
7. The combination with an evacuated 45 container, of a perforated partition dividing the interior thereof into two chambers, means for maintaining a distinct rectifying arc in each of said chambers, and means for extinguishing either of said arcs if it attempts to strike through the perforation in 50 said partition.
8. The combination with an evacuated 55 container, of a perforated partition dividing the interior thereof into two chambers, means for maintaining a distinct rectifying arc in each of said chambers, and magnetic

means for extinguishing either of said arcs if it attempts to strike through the perforation in said partition.

9. The combination with an evacuated 65 container, of a perforated partition dividing the interior thereof into two chambers, means for maintaining a distinct rectifying arc in each of said chambers, and means for providing a magnetic barrier between said arcs.

10. The combination with an evacuated 70 container, of a perforated partition dividing the interior thereof into two chambers, means for maintaining a distinct rectifying arc in each of said containers, and means for providing a magnetic blowout adjacent the perforation in said partition.

11. The combination with an evacuated 75 container, of a perforated partition dividing the interior thereof into two chambers, means for maintaining a distinct rectifying arc in each of said chambers, and a magnet external to the container and embracing the 80 perforated portion of said partition between its poles, whereby a magnetic blowout field is maintained in said perforation.

12. The combination with an evacuated 85 container, of a plurality of anodes therein and insulated therefrom, a pair of cathodes therein and also insulated therefrom, means for maintaining a rectifying arc between a portion of said anodes and one of said 90 cathodes, means for maintaining an additional arc between the remainder of said anodes and the other cathode, and a magnetic barrier between said arcs to prevent 95 their coalescence.

13. In a rectifying system, the combination 100 with a plurality of sources of alternating current, of means for producing a like number of rectifying arcs, and means for connecting said elements in alternation in a series circuit, said arcs being operated in a common chamber.

14. In a rectifying system, a closed 105 container and means for maintaining two distinct rectifying arcs therein, the respective cathodes being at different potentials.

15. In a rectifying system, a closed 110 container, and means for maintaining two distinct rectifying arcs therein, the respective cathodes being at different potentials and included in a common circuit.

In testimony whereof, I have hereunto 115 subscribed my name this 12th day of March, 1915.

DR. FRIEDRICH W. MEYER.
